DISPLAY RACK

William L. Burkhard, Denver, Colo., assignor to
 Gates Rubber Company, Denver, Colo., a corporation of Colorado

Application July 2, 1945, Serial No. 602,829

3 Claims. (Cl. 211—87)

This invention relates to improvements in display racks.

In places where articles, such as belts, are sold, it is desirable to provide racks on which they can be displayed and where they may be separated into groups of different sizes.

It is the object of this invention to produce a display rack of a simple and substantial construction that can be manufactured at a moderate price and assembled with a minimum of labor.

It is another object to produce a rack, for the purpose described, which shall have such a construction that it can be readily disassembled for shipment.

Another object is to produce a rack of such a construction that the supporting brackets, although readily removable, will be held firmly against movement in any direction.

The above and any other objects that may become apparent as the description proceeds are obtained by means of a construction and an arrangement of parts that will now be described in detail, and for this purpose reference will be had to the accompanying drawing in which the invention has been illustrated in its preferred form, and in which:

Figure 1 is a perspective view, partly broken away, showing the bracket fully assembled and in operative position;

Figure 2 is a section taken on line 2—2, Figure 1; and

Figure 3 is a section taken on line 3—3, Figure 1.

In the drawing reference numeral 5 designates the web of an elongated sheet channel, whose flanges have been indicated by reference numeral 6. Extending from and formed integral with the upper flange is metal strip 7 that is provided with spaced openings 8 for the reception of screws or nails by means of which it may be secured in place on a wall. Strip 7 is also provided with a plurality of pairs of tongues 9 designed for holding paper squares 10 on which the sizes and prices of the belts may be marked. A plurality of arms or brackets 11 are provided for supporting the belts or other articles. The arms are preferably formed from wire and are, broadly speaking, in the form of elongated V's, having an upper arm 12 and a lower arm 13. The ends of the arms are bent so as to provide hooks 14 that extend in opposite directions and lie in the plane of the arm.

The channel is provided with groups of holes into which the hooked ends of the arms extend

in the manner shown in Figure 2. The web has an upper hole 15 and a lower hole 16 for each group and the flanges have corresponding holes 17. The four holes 15, 16 and 17 are all in the same transverse plane and are preferably positioned adjacent the corners of the channel. Holes 16 are elongated in the direction of the transverse plane to such a length that the hook on arm 13 can be inserted through it. The other holes have a size slightly larger than the diameter of the wire.

Let us now consider Figure 2 from which the arm is removed in the following manner. Pressure is exerted on arm 13 in an upward direction at point 18, raising the arm sufficiently to disengage the hook from hole 17 in the lower flange. The arm is now rotated clockwise until the hooked end of arm 13 is withdrawn through hole 16 and the rotary movement continued until 20 the hook on arm 12 is disconnected from the channel.

The arm is replaced by a movement reverse to that just explained.

It will be obvious that the arms will be held quite firmly against movement relative to the channel. Although holes 17 have been shown quite near the corners of the channel, they may be spaced farther away, if desired. When the sheet metal part is formed, it may be braced by 30 a plurality of gussets 19 pressed from the metal or secured thereto by welding.

It is evident that the materials used can be of any strength and therefore the brackets may be designed for the support of materials of any weight.

Particular attention is called to the construction by means of which the supporting arms are detachably connected with the channel.

Having described the invention, what is 40 claimed as new is:

1. A display bracket comprising, an elongated channel whose web is provided with two holes, one adjacent each corner, and whose flanges each has a hole, the four holes being positioned in 45 the same vertical plane, one of the holes in the web having a greater dimension in the vertical plane than the other, and a flexible elongated V-shaped arm having the free ends provided with oppositely extending hooks lying in the plane of the arm, the ends of the arms extending through the holes in the web and the hooks projecting into the holes in the flanges.

2. A display bracket in accordance with claim 1 in which one of the flanges has an integral strip lying in a plane parallel with the web and

provided with holes for the reception of securing means.

3. A supporting arm for use with a display bracket comprising an elongated sheet metal channel whose web has two holes of unequal size, one near each corner and whose webs have each one hole, the four holes lying in the same vertical plane, the arm having the shape of an elongated

V, the free ends being bent outwardly in opposite directions to provide hooks lying in the plane of the arms, the free ends of the arms being adapted to extend through the holes in the web, the hooks being adapted to extend into the holes in the flanges.

WILLIAM L. BURKHARD.
